UNITED STATES PATENT OFFICE

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY

MOUNTING FOR ROCK DRILLS

Application filed December 24, 1930. Serial No. 504,522.

This invention relates to mountings, but more particularly to a mounting for rock drills of the hand held type.

One object of the invention is to enable a rock drill of this type to be conveniently used as a drifter for drilling horizontal and inclined holes.

Another object is to enable the rock drill to be quickly disposed in operative position on the mounting without requiring the manipulation of clamping or securing means.

Other objects will be in part obvious and in part pointed out hereinafter.

In the drawing accompanying this specification and in which similar reference characters refer to similar parts,

Figure 1 is a longitudinal elevation, partly in section, of a mounting constructed in accordance with the practice of the invention and illustrating the manner in which it may be applied to a hand held rock drill and a shell which forms a support for the mounting,

Figure 2 is a transverse view taken through Figure 1 on the line 2—2 looking in the direction indicated by the arrows; and

Figure 3 is a sectional plan view taken through Figure 1 on the line 3—3 looking in the direction indicated by the arrows.

Referring to the drawing and at first more particularly to Figure 1, A represents a rock drill of the hand held type comprising a cylinder B, a front head C and a back head D. These parts serve as a casing for the rock drill and are clamped securely together by side bolts E. In the back head D are apertures F through which the side bolts E extend and the front head C is provided with ears G having apertures H to accommodate the side bolts E.

In accordance with the usual practice the front head C acts as a guide for a drill steel J, and on the front head C is a steel retainer K having a yoke L which may partly encir-

cle the drill steel J to provide a seat for a collar O carried by the drill steel J.

Being of the hand held type, the drill A or, more specifically, the back head D is provided with a handle P comprising a pair of rearward extensions Q which may be integral portions of the back head D. Between the rear ends of the extensions Q is a grip portion R which, when the drill is being hand supported, may be gripped by the operator 50 for holding the drill in the proper position with respect to the work.

The mounting constructed in accordance with the present invention comprises a carriage S having on opposite sides thereof longitudinally extending guide ribs T adapted to slide within guideways U of a rock drill shell V, such as is commonly employed for guiding and supporting rock drills of the drifter type with respect to the work. The shell V has a cone W for cooperation with a suitable clamping device (not shown) whereby the shell may be clamped to a supporting column or bar.

Near the front end of the carriage S and disposed on opposite sides thereof are guide lugs X so spaced with respect to each other as to enable the ears G of the front head C to lie therebetween. The free ends of the lugs X are in the form of introverted hooks Y which overlie the ears G. The space defined by the lugs X and the hook portions Y is preferably somewhat larger than the portion of the front head C which it accommodates so that the ears may be readily disposed between the lugs during the operation of placing the drill A upon the carriage S.

In order to assure the correct position of the rock drill A with respect to the carriage S during the time the rock drill is being actuated in the direction of the work, the carriage S is provided at its rear end with a cross member Z having a groove b therein adapted to accommodate the grip portion R. The cross member Z is preferably provided with 85 90

an integral hook *c* which overlies the grip member *R* to assure against accidental dis-
placement of said grip member from the
groove *b*. The cross member *Z* as arranged
6 acts as an abutment for the drill *A* and serves
to prevent endwise movement of the drill *A*
with respect to the carriage *S* during the
time the drill *A* is being actuated towards
the work.

10 In order to assure simultaneous withdrawal
of the rock drill *A* and the carriage *S* the
back head *D* is provided with a hook *d*
which extends into the shell *V* and has an
inclined surface *e* adapted to engage a sim-
ilar surface *f* of a rib *g* forming a part of the
carriage *S*, and in this instance lying beneath
the cylinder *B*. The rib *g* is, however, so lo-
cated that the rock drill *A* is capable of a
limited degree of movement in a forwardly
20 direction on the carriage *S* before bringing
the hook *d* into engagement with the rib *g*.

To the end that the carriage *S*, together
with the rock drill *A*, may be conveniently
actuated longitudinally of the shell *V*, the
25 cross member *Z* is provided with an aperture
h to receive a feed nut *j* having a head *k*
which seats against one end of the cross mem-
ber *Z*. On one end of the feed nut *j* is a col-
lar which seats against the cross member *Z*
30 and the other end of said feed nut is exter-
nally threaded to accommodate a nut *o*
whereby the feed nut *j* may be clamped fixed-
ly in the cross member *Z*. The feed nut *j*
is internally threaded for the accommoda-
35 tion of a feed screw *p* journaled with its
front end *q* in a bearing block *r* secured to
the shell *V*. The opposite or rear end of
the feed screw *p* may be similarly supported
40 and may be provided with a crank handle
(not shown), such as is commonly used for
rotating the feed screw to actuate the rock
drill longitudinally of the shell.

The carriage *S* may be provided with ad-
ditional abutment means at its front end,
45 such as an extension *s*, having lugs *t* which
lie in the path of the ears *G* and with re-
spect to which said lugs are spaced about
the same distance as that distance normally
existing between the inclined surfaces *e* and
50 *f*.

In practice, assuming the carriage *S* to be
in the proper assembled position in the shell
V, the rock drill *A* may be placed upon the
carriage *S* with the front head lying be-
55 tween the lugs *X*. By raising the rear end
of the rock drill and sliding said rock drill
in a forwardly direction the grip member *R*
will pass over the cross member *Z* and the
ears *G* will enter the space between the lugs
60 *X*. The rock drill *A* may then be moved
forwardly with respect to the carriage *S* un-
til the grip member *R* reaches a position from
which it may be lowered past the hook *c*.
Thereafter the grip member *R* may be
65 dropped into the groove *b* and the entire
apparatus will be in readiness for use for
drifting purposes.

Upon setting the hammer drill *A* in oper-
ation to direct the blows of the percussive
element of the rock drill against the drill
steel *J* the feed screw *p* may be rotated in
70 the usual manner to actuate the carriage *S*
and the rock drill *A* in the direction of the
work. Upon completion of a drill hole or
whenever it becomes necessary to change drill
75 steels the feed screw *p* may be turned in an
opposite direction.

It is conceivable that under some conditions
of drilling the rock drill *A*, together with the
drill steel *J*, will be readily retracted by the
carriage *S* without necessitating the shifting
80 of the rock drill from the position which it
occupies during the feeding movement. In
the event however that friction between the
wall of the drill hole and the drill steel *J*
85 is sufficiently great to resist the retractive
movement of the rock drill *A*, the carriage *S*
may be retracted independently of the rock
drill until the rib *g* engages the hook *d* and
the lugs *t* engage with the ears *G*. The en-
90 tire apparatus may then be moved rearward-
ly on the shell *V*.

After the drill steel *J* has been changed
the feed screw *p* may again be rotated to
advance the carriage *S* and the rock drill *A*.
95 This forward movement of the carriage *S*
will move the cross member *Z* into abutting
position against the grip member *R* and the
ears *G* will then lie between the lugs *X* where-
100 by the front portion of the drill will be held
in approximate alignment with the drill
steel *J*.

The present invention has been found to
be extremely desirable in connection with
drilling apparatus such as that described.
105 This is due to the fact that the carriage *S*
as constructed comprises only a single piece
which will efficiently guide a hand held drill
during its use as a drifter without necessitat-
ing the use of a multiplicity of clamping de-
110 vices to secure the rock drill to the carriage.

I claim:

1. A mounting for a rock drill, comprising
in combination with a rock drill casing and
a handle thereon, a saddle to support the
drill, guide lugs on the saddle to loosely
115 engage the casing, an abutment on the car-
riage having a groove to receive the handle
and acting against the handle to prevent end-
wise movement of the rock drill in one direc-
tion with respect to the carriage, a rib on
120 the saddle, and a hook on the casing adapted
to engage the rib for limiting movement of
the rock drill with respect to the casing in
an opposite direction.

2. A mounting for a rock drill, comprising
in combination with a rock drill casing and
a handle thereon, a saddle to support the
drill, guide lugs on the saddle to loosely
125 engage the casing, an abutment on the car-

riage having a groove to receive the handle and acting against the handle to prevent end-wise movement of the rock drill in one direction with respect to the carriage, guide ribs 5 on the carriage for slidably engaging a rock drill shell, a feed nut carried by the carriage, and a feed screw cooperating with the feed nut for actuating the carriage and the rock drill along the shell.

10 In testimony whereof I have signed this specification.

RUSSELL H. WILHELM.
